(57) **CLAIM**

We claim the ornamental design for a module for a modular irrigation controller, as shown and described.

DESCRIPTION

FIG. 1 is a top, front perspective view of one embodiment of a module for a modular irrigation controller according to our new design;

FIG. 2 is a bottom, rear perspective view of the module of FIG. 1;

FIG. 3 is a top plan view of the module of FIG. 1;

FIG. 4 is a bottom plan view of the module of FIG. 1;

FIG. 5 is a left side elevation view of the module of FIG. 1;

FIG. 6 is a right side elevation view of the module of FIG. 1;

FIG. 7 is a front elevation view of the module of FIG. 1;

FIG. 8 is a rear elevation view of the module of FIG. 1;

FIG. 9 is a top, front perspective view of a second embodiment of a module for a modular irrigation controller according to our new design wherein electrical connections on the top of the module are illustrated in broken lines for illustrative purposes and form no part of the claimed design;

FIG. 10 is a bottom, rear perspective view of the module of FIG. 9 wherein electrical connections, screws, mounting pegs and tabs on the bottom surface of the module are illustrated in broken lines for illustrative purposes and form no part of the claimed design;

FIG. 11 is a top plan view of the module of FIG. 9;

FIG. 12 is a bottom plan view of the module of FIG. 9;

FIG. 13 is a left side elevation view of the module of FIG. 9;

FIG. 14 is a right side elevation view of the module of FIG. 9;

FIG. 15 is a front elevation view of the module of FIG. 9; and,

FIG. 16 is a rear elevation view of the module of FIG. 9.
